(57) **CLAIM**

The ornamental design for a clothes rack, as shown and described.

DESCRIPTION

FIG. 1 is a top, front, left-side perspective view of a clothes rack showing my new design with its holders in a horizontal position;

FIG. 2 is a front elevational view thereof;

FIG. 3 is a top plan view thereof;

FIG. 4 is a bottom plan view thereof;

FIG. 5 is a left side elevational view thereof, the right side elevational view being mirror symmetrical thereto;

FIG. 6 is a rear elevational view thereof; and,

FIG. 7 is a front elevational view of the clothes rack of FIGS. 1 to 6 with its holders in a vertical position.
